UNITED STATES PATENT OFFICE.

CHRISTIAN MAERTEN, OF NORTH TONAWANDA, NEW YORK, ASSIGNOR TO ARTIZAN FACTORIES, INC., OF NORTH TONAWANDA, NEW YORK.

MECHANICAL MUSICAL INSTRUMENT.

Application filed January 7, 1924. Serial No. 684,715.

This invention relates to improvements in automatic musical instruments of that kind in which the playing of the instrument is controlled by a perforated note sheet or element which cooperates with a tracker or duct bar over which it travels to control the operation of pneumatic actuating means for the instrument. More particularly the invention relates to instruments of this character in which a plurality of the same pneumatic playing action note sheets or elements wound on spools or rolls are employed and one note sheet is rewound on the spool simultaneously with the unwinding or travel of another note sheet for playing the instrument, so that a second note sheet can be started for playing therefrom as soon as the selection or selections of the first note sheet is or are completed, without waiting for the rewinding of the first note sheet.

One object of the invention is to produce a practical, efficient and desirable musical instrument of the type mentioned. Other objects of the invention are to provide simple, practical and reliable automatic mechanism for propelling, starting and stopping the note sheets in such manner that each note sheet will be rewound immediately upon the completion of its selection or selections and a second note sheet will be started for playing the selection or selections thereon simultaneously with the commencement of the rewinding of the first note sheet; also to provide simple and reliable means for cutting off each tracker from the playing pneumatics during the rewinding of the note sheet for said tracker, to thereby prevent interference with the control of the instrument by another note sheet and the improper sounding of the speaking devices; also to provide efficient means for rewinding the note sheets more rapidly than they travel when playing the instrument and for arresting the rewinding of a note sheet as soon as it is completely rewound while the playing note sheet nevertheless continues in operation; also to provide convenient means for manually starting, stopping and causing the rewinding of each note sheet at will, so as to enable the user to play any one or more of the selections on the several note sheets as may be desired; and also to improve and simplify musical instruments of the character mentioned in various respects as will appear

from the following description and claims. 55

In the accompanying drawings:

Fig. 1 is an elevation of the operating mechanism of a plural note sheet instrument embodying my invention.

Figs. 2 and 3 are diagrammatic views of 60 the mechanical actuating and pneumatic controlling devices for the two note sheets and trackers arranged so as to clearly show the relation of the parts, the parts being shown in different positions in the two figures. 65

Fig. 4 is an elevation partly in section, of the detachable units comprising the automatic cutoff means for the trackers, the note sheet pneumatic controls and the clutch controls for the note sheet driving mechanism. 70

Fig. 5 is a transverse sectional elevation of the valve chest for the pneumatically controlled stop and start valves, on line 5—5, Fig. 18.

Fig. 6 is a similar view thereof on line 75 6—6, Fig. 18.

Fig. 7 is a plan view of one of the hand actuated valves for manually controlling the movements of the note sheets.

Fig. 8 is a vertical section thereof on line 80 8—8, Fig. 7.

Fig. 9 is a sectional elevation of the mechanism for cutting off the tracker of each note sheet during the rewinding of the note sheet. 85

Fig. 10 is a horizontal section of the cut off valve shown in Fig. 9, together with the rewind and playing pneumatics for the same note sheet.

Fig. 11 is a similar view of the rewind 90 and playing pneumatics shown in Fig. 10, the section being on line 11—11, Fig. 9.

Fig. 12 is a similar view thereof showing another position of the parts.

Fig. 13 is a fragmentary face view, partly 95 in section of, the dust collector ports which are arranged in the passages between the trackers and the primary pneumatics.

Fig. 14 is a fragmentary sectional elevation similar to Fig. 9 of the cut-off valve 100 and the diaphragm board and diaphragms controlled by the cut-off valve, in diaphragm closing position.

Fig. 15 is a fragmentary sectional elevation of the diaphragm board and the dia- 105 phragms controlled by the other cutoff valve with these diaphragms in open position.

Fig. 16 is a fragmentary face view of the

diaphragm board shown in Figs. 9 and 14, removed from the instrument.

Fig. 17 is a fragmentary horizontal section thereof on line 17—17, Fig. 9.

Fig. 18 is a sectional elevation of the removable valve chest containing the stop and start valves for the note sheets, on line 18—18, Fig. 5.

Fig. 19 is an elevation, partly in section, of the removable plate of the valve chest showing the air control passages for the rewind and winding valves.

Figs. 20 and 21 are horizontal sections on lines 20—20 and 21—21 respectively Fig. 18 of the rewind and winding valve chest.

Fig. 22 is a view of one of the note sheets and its tracker showing the relative positions of the playing and rewind perforations in the note sheet.

Fig. 23 is a fragmentary perspective view showing the means for breaking suction in the main suction bellows.

The instrument shown in the drawings, see Figs. 1 and 9, comprises generally the usual wind chest 10 containing a plurality of pneumatics 11 and pallets 12 actuated thereby for controlling the admission of compressed air from the wind chest to the various speaking instruments or devices 13, a main suction bellows or reservoir 14, a suction passage 15 leading therefrom to a main suction chamber 16, for creating suction in a plurality of suction passages 17 controlled by primary pneumatics or valves 18 actuated by air pressure admitted by the note perforations of the note sheets on the trackers A' B' of the note sheet winding and rewinding mechanism A B, respectively. There is a valve 18 for each note of the note sheets and, as usual, when the valves 18 are actuated by air pressure from the trackers, the speaking pneumatics 11 are collapsed to open the pallets 12 and thereby cause the instruments 13 to speak.

The two note sheet winding and rewinding mechanisms are preferably constructed as follows. As they are alike, only one will be described in detail, the same reference characters being used in both mechanisms.

The note sheet, as usual, is secured on a spool or delivery roll 20 from which it is adapted to pass over the tracker and be wound onto a take-up roll 21, when the note sheet is being operated to play the instrument. Fig. 1 shows the note sheet mechanism B in playing or winding position and the mechanism A in rewinding position. Each mechanism is preferably mounted on a separate frame 28 independently secured

in the instrument so that each mechanism forms in itself a complete separable unit. A drive shaft 22 is used in each mechanism provided with a pair of drive gears 23, 24, meshing respectively with a pinion 25 on a shaft 25^a of the delivery roll 20, and a

gear 26 on a counter shaft 27 journaled on the frame 28. The counter shaft 27 also carries a pinion 29 meshing with a gear 30 on the shaft 31 of the take-up roll 21. The pinion 25 and the gear 30 are loose and adapted to move endwise on their respective shafts 25^a and 31, and each of these gears is provided with teeth or parts adapted to engage with complementary parts on clutch members 33 and 34 fixed on the shafts 25^a and 31 respectively. These clutch members 33 and 34 and sliding gears 25 and 30 are so arranged and actuated that when either of the gears is moved to engage its clutch member and thereby cause its shaft to rotate, the other gear will be moved out of engagement with its clutch. The gear 30 is the winding gear and the gear 25 the rewinding gear. The means shown for alternately actuating these gears for winding and rewinding the note sheets includes forked rock arms 35 and 36 fixed to a rock shaft 37 journaled in the frame 28 and engaging respectively in grooved hubs on the gears 25 and 30 so that a partial turning of the shaft will swing one gear into and the other gear out of clutch-engaging position. The gears 25 and 29 are of such width that the sliding gears will always remain in mesh with the gears that drive them. In Fig. 1 the winding gear 30 of the mechanism B is in winding position and the rewinding gear 25 of the mechanism A is in rewinding position, while the gear 25 of mechanism B and gear 30 of mechanism A are running free on their shafts, being both disconnected from their clutch members. The rock shafts 37 are actuated by means hereinafter described for simultaneously rocking both shafts, so that while one note sheet is being wound on the roller 21 of one of the mechanisms A, B for playing the instrument, the other note sheet will be rewinding on the roll 20 of the other mechanism. The drive shafts 22 of the two mechanisms A and B are suitably connected to rotate together, preferably by a flexible or universal coupling 38 which allows more or less misalignment of the shafts when securing the mechanisms in the instrument.

Means are provided for rotating the drive shafts 22, said means preferably including an adjustable, variable speed device C, and means for actuating the same to disconnect the driving mechanism from the shafts 22, while the main drive shaft 40 is running. As shown, the main drive shaft 40 is geared to and drives a counter shaft 41, which in turn is geared to and drives the variable speed mechanism C. The shaft 40 has crank portions, connected by pitmen 42 to pumping bellows 43 for maintaining a constant suction in the suction bellows 14. The means for disconnecting the drive shafts 22 from the variable speed device C includes a

bearing slide 45, see Figs. 1 and 23, movable in a fixed guide block 46 on one end of the instrument case and having pivoted thereto one end of a transmission shaft 47. The 5 shaft 47 has a flexible or universal connection with one end of the drive shaft 22 of the winding mechanism B and also carries a friction wheel 48 adapted to engage a cone wheel 49 of the variable speed device C. A 10 crank shaft 50 journaled in the case of the instrument is provided with an eccentric or cam 51, (Fig. 23) engaging in an aperture of the bearing slide 45, so that by turning the crank shaft, as by the crank handle 52 on its 15 outer end, the cam will lift the slide 45 and disengage the friction wheel 48 from the cone wheel 49. The friction wheel is splined on the shaft 47 and is adapted to be adjusted lengthwise thereon to different positions 20 relative to the cone 49 for varying the speed of travel of the note sheets as may be required.

Each of the note sheet winding and rewinding mechanisms A and B is provided 25 with a playing and a rewinding pneumatic for operating the clutches of said mechanism, a pneumatically controlled automatic cutoff mechanism for rendering inoperative the tracker for each note sheet during the 30 winding of that note sheet, and means associated with the winding and rewinding pneumatics of the mechanisms A and B for actuating the clutches of the two mechanisms A and B. The clutch operating pneumatics, 35 cutoff valve and clutch actuating means for each of the mechanisms A and B are preferably arranged as a separate detachable set or unit, secured within the instrument to a suitable part thereof as for instance to a 40 panel 54 secured to the side wall of the instrument case. The unit for the control of the mechanism A is designated generally as D, while the unit for the mechanism B is designated generally as D'. 45 As shown in the drawings see Figs. 4, 9 and 12, the unit D' includes a playing or start and stop pneumatic 55, and a rewind pneumatic 56, secured on opposite faces of a board 57 forming part of a bracket 58, detachably secured to the panel 54. Vertical 50 suction passages 59 and 60, preferably formed in the panel 54, communicate respectively, through passages 59^a and 60^a in the bracket 58 and board 57, with the pneumatics 55 and 56. The passages 59, 60 communicate with the suction bellows 14, through a conduit and a control valve chest E. The pneumatics 55 and 56 are connected to each other as by a bar 63 pivoted to the 55 movable walls of the pneumatics, so that when one of the pneumatics is collapsed by suction therein, the other pneumatic is positively expanded. The detachable unit D for the other mechanism A is similar to the unit D' and includes a playing pneumatic 65, and a rewinding pneumatic 66 on a removable bracket 67, the pneumatics 65, 66 being under the control of suction from passages 68, 69, respectively, leading from the valve chest E. The pneumatics 65, 66 like 70 the pneumatics 55, 56, are connected by a bar 63^a, so that movement of one pneumatic is imparted to the other.

In the position of the parts as shown in Figs. 1 and 2, the note sheet mechanism B is 75 in playing position, and the playing pneumatic 55 of unit D' is collapsed and the rewind pneumatic 56 is expanded or inoperative, while the note sheet mechanism A is in rewinding position. Consequently, the 80 rewind pneumatic 63 of unit D is collapsed and the playing pneumatic 65 is expanded or inoperative.

The present invention contemplates means 85 of novel construction, for causing the simultaneous actuation of the clutches of the mechanisms A and B through pneumatic control of the playing pneumatics 55, 65 and rewind pneumatics 56, 66, and through them, 90 of mechanical devices connected to and adapted to actuate the clutch rock shafts 37.

This pneumatic controlling means includes 95 the valve chest E, before mentioned and which is preferably detachably secured on the panel 54. A suction chamber 62 in this chest connects with the suction conduit 61 and connects by way of ports 70 with a series of valve chambers 71 which are in connection respectively with the passages 59, 60, 100 68, 69 which lead to playing and rewinding pneumatics 55, 65, 56, 66. There are, therefore, four of the valve chambers 71, and each chamber is connected to the atmosphere by means of a port 72, arranged opposite the port 70. Each of the chambers 71 contains 105 a valve adapted to be actuated to alternately close one and open the other of the ports 70, 72, connected with its particular valve chamber. Two of these valves designated 74, 75, 110 are the playing valves and are arranged in the chambers which connect respectively with the suction passages 59, 68, while the other two valves 76, 77 are rewind valves and are in the chambers which connect respectively with the suction passages 60, 69. Each 115 valve is provided with a stem which passes downwardly through the port 70 and through the suction chamber 62 with its lower end connected with the movable wall or diaphragm of an actuating pneumatic or pouch 78. The pouch for one of the playing valves 74, is connected by a passage 79, and tubes or conduits 81, 81^a with a duct 83, in the tracker B' and the pouch for the other winding valve 75 is similarly connected by a passage 80 and conduits 82, 82^a with a duct 84 in the other tracker A'. The duct 83 or 120 84 of each tracker is controlled by a winding or starting perforation 85 at the beginning 125 end of the note sheet for that tracker, see 120

Fig. 22. The pouches for the two rewind valves 76, 77 are similarly connected by passages 86, 87 and tubes or conduits 88, 88^a and 89, 89^a with ducts 90, 91 in the trackers B' and A' respectively, each of which ducts is controlled by a rewind perforation 92 at the finish end of the cooperating note sheet, see Fig. 22. As shown in Figs. 4-6 and 18-19, the passages 79, 80, 86, 87 of the valve chest E are connected to the tubes 81, 82 and 88, 89 by means of holes in a cover plate 93 removably secured as by screws 94 on the front of the valve chest thereby effecting ready access to the valves and pouches. This cover plate is further provided with a series of branch passages arranged as follows:—

The conduit 81 leading from the tracker B' is provided in the plate 93 with a branch passage 95 which ends in a bleeder port 95^a communicating with the chamber 71 of the rewind valve 76, while the other conduit 88 from the tracker B' is provided with a similar passage 96 and bleeder port 96^a in communication with the chamber of the playing valve 74. Similarly, the conduit 82 from the tracker A' has a branch passage 97 and a bleeder port 97^a communicating with the chamber of the rewind valve 77, and the conduit 89, also from the tracker A' has a branch passage 98 and bleeder port 98^a communicating with the valve chamber of the playing valve 75. In this connection, the Figure 19 should be read as being in register with Fig. 18, wherein the bleeder ports 95^a, 96^a, 97^a, 98^a relatively to the valve chambers are all indicated by double broken line circles. The purpose of these branch passages and bleeder ports will be explained later.

The mechanical connections between the winding and rewind control units D, D' for causing the simultaneous actuation of the clutch rock shafts 37 of the mechanism A and B are constructed and arranged as follows: see Figs. 1-8.

The rock shaft 37 of the mechanism A is provided with an arm 100, connected by a link 101 to the coupling bar 63^a of the pneumatics 65, 66, while the rock shaft 37 of the mechanism B is provided with an arm 102, 50 connected by a link 103 to the coupling bar 63 of the pneumatics 55, 56. Suitably pivoted, for instance on the bracket 67 of unit D, is a latch 104, one end of which is normally held against a stop pin 105 on the 55 movable wall of the playing pneumatic 65 by a suitable spring 106. The opposite end of this latch is connected, as by the link 107 to one end of a bell crank 108 suitably pivoted adjacent the unit D'. The other end 60 of the bell crank engages the end of the bar 63 of unit D'. A second latch 110 pivoted for convenience on the bracket 57 of unit D' has one end thereof held against a stop pin 111 on the movable wall of pneumatic 55 65 by a spring 112. The other end of this

latch is connected by a link 113 to one end of a second bell crank 114 pivoted at 115 adjacent the unit D and the other end of the latter bell crank engages the end of the bar 63^a of unit D. It is desirable that the speed of travel of the note sheet that is being rewound should be greater than that of the note sheet which is being played, so that the rewinding note sheet will be completely rewound and come to rest before the other sheet has been played, thereby ensuring positively that the rewound sheet will be in readiness to be started as soon as the selections on the other sheet are finished. Consequently, as soon as either note sheet has been rewound, both clutches of the driving mechanism for that sheet must be moved to a neutral position so that both rolls 20, 21 of that mechanism will be idle. The stop pins 105, 111 of the units D, D' cooperate with stop shoulders 117, 118 on the latches 104, 110, respectively for this purpose.

The operation of the instrument as thus far described is as follows:

Assuming the parts to be in the relative positions shown in Figs. 1 and 2, with the mechanism B in position for playing the instrument, that is, with its note sheet feeding over tracker bar B' onto the take up roll 21, and the mechanism A in rewinding position, with its note sheet rewinding onto delivery roll 20, then the playing pneumatic 55 will be collapsed to hold winding clutch 34 of mechanism B in driving position, while rewind pneumatic 66 will be collapsed to hold rewind clutch 33 of the other mechanism A in position for rewinding that note sheet. At this time the playing pneumatic 65 is expanded and the coupling bar 63^a of unit D is held to the right in Figs. 1 and 2, thus acting through bell crank 114 and link 113 to hold the free end of latch 110 elevated so that stop pin 111 has passed the shoulder 118 and allowed the playing pneumatic 55 to collapse. While pneumatic 55 is collapsed, the companion pneumatic 56 is expanded and holds coupling bar 63 to the left and, owing to the upward pull of spring 106 the free end of latch 104 is maintained in engagement with its stop pin 105. As the note sheets rewind faster than they unwind, the starting perforation 85 of note sheet of mechanism A will register with the duct 84 of tracker A', while the other note sheet is still traveling in the playing direction. Atmospheric pressure thus passes by way of duct 84, conduits 82^a, 82, to the diaphragm or pouch 78 of playing valve 75, expanding the diaphragm and lifting the valve to close the air inlet port 72 and open 115 the valve chamber to the suction through port 70. This allows suction to act through passage 68 on the playing pneumatic 65, causing it to partially collapse and through the bar 63^a and link 101 to rock the shaft 37 120 125 130

and actuate the clutches of mechanism A. This movement, however, is limited by the engagement of the stopper 105 with the shoulder 117 of latch 104, which shoulder 5 is so positioned that both clutches of mechanism A will be held in neutral position, whereby its note sheet will be arrested and prevented from movement in either direction. When the valve 75 is moved as thus explained, to collapse the playing pneumatic 65, the suction will act on the diaphragm 78 for the rewinding valve 77 through the branch passage 97, thereby collapsing this diaphragm and moving said valve 77 to open 10 its air inlet port 72 and close its suction port 70. This valve 77 until this time had been in its upper position, see Fig. 2, closing its air inlet port, so that suction from suction chamber 62, acting by way of passage 69 on the 15 rewind pneumatic 66, caused the rewinding of the note sheet, of mechanism A. However, as soon as air pressure enters the chamber of valve 77, this air pressure will pass around the valve and through the passage 20 69 to rewind pneumatic 66, causing it to expand. It is necessary, after the winding valve 75 has been lifted, to maintain it in such upper position to prevent the entrance of air to the passage 68, as otherwise the 25 air pressure would enter and expand the pneumatic 65 and thus move the clutches of mechanism A back into playing position. This is preferably accomplished by a spring 30 120 Fig. 18, which acts on the stem of the valve 75, and holds the valve up against the air port. This it can do until the perforation 85 of the note sheet is moved out of register with the duct 84, which takes place when the note sheet is started in the opposite direction, for playing the instrument. A similar spring 121 for a like purpose is 35 also provided for the other winding valve 74.

The note sheet operating mechanism A 40 will remain in neutral position until the note sheet of the other mechanism B has been completely unwound, whereupon the rewind perforation 92 of this note sheet will register with the rewind duct 90 of tracker B', allowing atmospheric pressure to pass by way 45 of conduits 88^a, 88, and passage 86 to pouch 78 of the rewind valve 76 to lift this valve and close its air inlet port 72 and open its suction port 70. Suction will then act by 50 way of passage 60 on the rewind pneumatic 55 of unit D', causing it to collapse and move bar 63 and link 103 to the right. The clutch shaft 37 of mechanism B therefore, will be rocked to move the clutches of 55 this mechanism to rewinding position and effect the rewinding of the note sheet of this mechanism B. When the valve 76 is thus raised to close its air inlet 72 it will also place the branch passage 95 in connection 60 with the suction which will then act through 65 said passage in the pouch diaphragm 78 of the playing valve 74 and thereby lower said valve to open its air inlet 72 and close its suction port 70. This permits atmospheric pressure to pass to playing pneumatic 55 by 70 way of passage 59. The reversing of pneumatics 55, 56, and movement of bar 63 and link 103 to the right, causes the bell crank 108 to swing and through the link 107 actuate the latch 104 of unit D so as to permit 75 stop 105 to pass shoulder 117. The pneumatic 65 is thus enabled to completely collapse, while the pneumatic 66 opens to its full extent. Therefore, the bar 63^a and link 101 will now complete their full movement to 80 the left and move the clutches of the mechanism A from the neutral position to starting position, and cause the note sheet to travel in the direction to play the instrument. When the note sheet of mechanism B is 85 fully rewound, the playing perforation 85 thereof will register with playing duct 83 of tracker B' and allow air pressure to pass through conduits 81^a, 81 and passage 79 to pouch 78 of winding valve 74, which is then, 90 as above explained in its lower position as shown in Fig. 18. The admission of air to the pouch of the valve 74, will now raise the valve, close its air port 72, and through the medium of the branch passage 96 and the 95 pouch diaphragm for the valve 76, the latter will open its air port 72 and the air will pass into passage 60 by way of chamber of valve 76 to rewind pneumatic 56. At the same time, owing to lifting of valve 74, suction 100 will act through passage 59 on winding pneumatic 55. Thus pneumatics 55, 56 will actuate the coupling bar 63 and link 103 tending to move the clutches of mechanism B to place them in playing position as before. However, the stop pin 111 and latch shoulder 118 of the unit D' will first arrest 105 the clutches in the neutral position, and the note sheet will remain stationary until the 110 rewind perforation 92, at the finish end of the other note sheet on mechanism A actuates its rewind mechanism, whereupon the bell crank 114 and link 113 will actuate the latch 110 to allow the stop 111 to pass the shoulder 118, and permit the playing and 115 rewind pneumatics 55, 56 to complete their movement to the left and so permit the note sheet on mechanism B to travel in the playing direction.

It is desirable to be able to actuate the winding and rewinding mechanisms for the note sheets at will, independently of the described automatic control by the note sheets, for instance, to repeat a desired selection on a note sheet or to rewind the note sheet and play one or another selection without waiting until the end of the note sheet is reached. For this purpose, hand-controlled means is provided preferably constructed as follows: F F' indicate hand controlling devices for 120 125 130

the mechanisms A and B respectively, operatively connected with the playing or winding and rewind conduits leading from their respective trackers A' B'. These devices 5 are alike and only one need be described. The device F, see Figs. 7 and 8, comprises a base plate 125 and a movable damper or lever 126 pivoted thereon. The plate 125 is provided with a through port 127 in which 10 is fitted a branched tubular fitting 128 to one branch of which is connected the playing conduit 82^a from the duct 84 of the tracker A'. The other branch of the fitting 128 connects with the duct 82 leading to the 15 pouch for the playing valve 75 in the valve chest E. Another port 129 and branched fitting 130 connects the rewind conduits 89^a and 89 from the duct 91 of tracker A' to the pouch of rewind valve 77. The upper ends 20 of the ports 127, 129 are normally closed by the lever 126 so that the conduits 82, 82^a and 89, 89^a form two continuous uninterrupted air passages from the tracker to the 25 valve chest E. The lever 126 is provided with a playing port 131 and a rewind port 132. The playing port 131 may be moved into register with the aperture 127 by swinging the lever 126, whereupon atmospheric pressure will be admitted to passage 30 82—82^a and will act the same as when admitted through the port 84 of the tracker A under the automatic control of the note sheet to cause the playing travel of the note sheet. The other port 132 of the lever may be similarly 35 brought into register with the aperture 129 by swinging the lever 126 into engagement with a stop 133, thus actuating valves 77, 75 and rewind pneumatic 66 just as when air pressure is admitted through the 40 port 91 of tracker A' under the automatic control of the note sheet. The spacing of the apertures 127, 129 and ports 131, 132 is such that only one port and one aperture can 45 register at one time. The ports of the device F function exactly as do the perforations 85, 92 of the note sheet relative to the ducts 84, 91 of the tracker A'. It should be noted that after one of the devices, as the device F, has been actuated, for instance to actuate 50 the winding pneumatic 65, the other device F' must then be moved to actuate its rewind pneumatic 56 and vice versa, exactly as if the note sheet perforation 85 on mechanism A and note sheet perforation 92 on mechanism B had acted on ducts 84, 90 of trackers A' B' respectively. These hand controlling devices are conveniently mounted on the shelf 135 which supports the note sheet operating mechanisms A and B. 55 The trackers A' B', as usual, are provided with a plurality of note ducts 140, 141 respectively, each duct being in communication with one of the primary valve boxes 18, and through the valve box with one or more of the 60 pneumatics 11 which actuate the pallets of

the pipes or speaking devices of the instrument. Each of the valve boxes 18 contains a valve 18^a adapted to connect one of the passages 17^a leading to the speaking pneumatics 11 or with the atmosphere under the control 70 of the note sheet. The valves 18^a of the valve boxes 18 are normally open to the atmosphere, and the suction between the passages 17, 17^a is broken. The speaking pneumatics 11 therefore will be then expanded, and the pallets 12 closed. Whenever a note perforation of the playing note sheet registers with one of the note ducts of the tracker, air pressure is admitted and passes to the corresponding valve box 18, and by expanding 75 a pouch 18^b therein, closes the valve 18^a to prevent the entrance of air through the port 18^c, and allow suction to act from the passage 17 connected with the particular valve box to the passage 17^a, thereby collapsing the 80 pneumatic 11, opening the pallet 12 and playing the speaking device connected thereto. 85

The note ducts, of the two trackers A' B' communicate with a pouch or diaphragm 90 box having pouches therein arranged in separate sets, one set for each tracker, and means are provided to close the set of pouches for either tracker during the rewinding of the note sheet over that tracker, so as to 95 prevent operation of the speaking pneumatics by that note sheet. The set of pouches for the other or playing tracker will remain open, so that as the note sheet passes over and opens the note ducts of the latter tracker air pressure may pass by way of the pouches to actuate the valves 18^a to connect the suction passages 17, 17^a and thereby cause the instrument to play. 100

An improved diaphragm or pouch box is 105 shown in the drawings, together with improved air cleaning or straining means in conjunction with the air passages between the ducts 140 and 141 of the trackers and the pouch box. The present instrument also includes improved means for operating the cutoff diaphragms or pouches, said means including a novel cutoff valve mechanism for each set of pouches, said cutoff valves being controlled by the actuating suction for the winding pneumatics 55 and 65 respectively. A 110 description of the preferred construction of the diaphragms, dust screens and cutoff valves follows:—

The pouch or diaphragm box, designated 115 145 preferably is removably secured on the front of a board 146 arranged beneath the shelf 135 so as to be readily accessible from the back of the instrument. The box 145 includes an upper row of pouches 147 in communication by conduits or passages 142, 142^a with the note ducts 140 of tracker A' and a lower row of pouches 148 in communication by conduits or passages 143, 143^a with the note ducts 141 of tracker B'. Each 120 125 130

pouch is in the form of a recess in the box 145 extending to the inner face thereof. All of the recesses of the pouches 147 are connected by a passage 150 with a suction conduit 151 extending in from the rear of the box 145, while the recesses of the other pouches 148 are similarly connected by a passage 152 to a suction conduit 153. A sheet 154 of suitable impervious flexible material is secured on the inner face of the box 145, as by an adhesive and extends over and closes the several pouch recesses, to form the movable walls or diaphragms of the pouches 147, 148.

15 When the box 145 is in position on the panel 146, each of the pouches 147 registers with the end of one of the passages 142 which connect with the ducts 140, and with the end of a passage 155. See Fig. 15.

20 Similarly, the pouches 148 register with the ends of passages 143 which connect with the ducts 141 and with the ends of passages 156. See Fig. 9. If one of the sets of pouches is acted upon by suction, for instance the pouches 148 and suction connection 153, the diaphragms thereof will be collapsed or drawn away from the ends of the passages 143 and 156, thereby establishing communication between these passages, as shown in Fig. 9. The other set of pouches 147 at this time will be under atmospheric pressure from its cutoff valve, as later explained, so that the diaphragm members thereof will seal the ends of passages 142 and 155 and prevent communication between the ducts 142 155. Each one of the note ducts 140 of tracker A' is duplicated in tracker B', and corresponding note ducts from both trackers are arranged to communicate with the same primary pneumatic 18 and through it to the speaking pneumatic instrument. For this purpose, each pair of ducts 155, 156 connects with a common passage 157 preferably in a strip 158, removably secured to the lower part of the board 146. Therefore corresponding note perforations in both note sheets will operate the same speaking devices but, by reason of the operation of the cutoff diaphragm, as will be explained, the speaking devices can not be operated by either note sheet while it is being rewound. Each passage 157 is connected by a tube 159 to the pouch 18^b of one of the valves 18. The passages 142^a 143^a, pouches 147, 148 and connecting passages are arranged in staggered relation for the sake of compactness.

25 The air strainers or dust collectors for the air passages 142^a 143^a are preferably formed in the upper portion of the board 146, and in a detachable cover board 160 secured thereto. As shown in Figs. 9 and 13, the detachable cover 160 is provided with an upper and lower row of pockets 161, 161^a respectively, which are in staggered relation to each other and are, in effect, offset enlargements of the passages 142^a 143^a, as they connect ports 162, 162^a and 163, 163^a respectively of these passages. The ports 162^a, 163^a leading respectively from the pockets 161, 161^a are covered by screens 164 of fine wire gauze or the like, removably seated in recesses 165 in the board 146. By this construction, practical, simple and readily accessible means are provided for screening the air admitted by the trackers. It often happens that small particles or fibers of paper from the note sheet and particles of dust pass into the tracker ducts. These are intercepted by the screens and collect in the large dust pockets 161, 161^a without obstructing the ducts and ports, and the removable cover 160 and screens 164 enables the pockets 161, 161^a to be readily emptied of accumulations and thus makes it possible for the ducts to be kept open and free from obstructions. Similarly, the removable pouch box or board affords ready access to the diaphragms for repairing or replacing them.

30 As before stated, the tracker cutoff for the pouches 147, 148 are operated under the control of cutoff pneumatics or valves cooperating with the winding pneumatics 55, 65 for the purpose of closing the note ducts for each tracker when the note sheet of that tracker is rewinding, while simultaneously allowing the note ducts of the other tracker to function for playing by the note sheet traveling over the latter tracker. This result is accomplished by means preferably constructed and operating as follows: The cutoff valves G G', Figs. 1-4 are arranged in valve chests 167, 168 which are detachably mounted on and form a part of the units D D' respectively, being preferably fastened by screws on the brackets 57, 58. The valve G', its valve chest 168 and connections are shown in section in Figs. 9 and 14. The valve G' comprises a stem portion and spaced valve disks 170, 171 thereon cooperating respectively with ports 172, 173, the disks 170, 171 being spaced apart so that when the upper disk closes the port 172, the other disk will open the port 173. The port 172 communicates directly with the atmosphere, while the port 173 opens into a chamber 174 connected by a conduit 175 with the suction passage 59 of the winding pneumatic 55. The valve chest 168 is provided with a duct 176 connecting both ports 172, 173 with a conduit 153^a formed in the panel 54 on the instrument case and connecting with the conduit 153 leading to the cutoff pouches 148. When, therefore, the valve G' is in its lower position, Fig. 9, the air inlet port 172 will be closed and the suction port 173 will be opened, thus connecting the pouches 148 with the suction passage 59 by way of conduits 153, 153^a, duct 176, chamber 174 and conduit 175. This suction draws the cutoff diaphragms 148 away from the ports 130

141^a, 156^a and establishes communication between said ports. The valve G' is actuated by a pneumatic preferably consisting of a diaphragm 177 over a chamber or pouch 178 arranged below the chamber 174. The diaphragm 177 is actuated by the opening and closing of an air inlet port 179 preferably arranged in the panel 54 of the case adjacent the rewind pneumatic 56 for mechanism B. 5 A spring or flap valve 180 is adapted, when the rewind pneumatic 56 is collapsed for rewinding the note sheet of mechanism B, to spring or move away from and allow air to enter the port 179. A conduit 181 connects 10 the port 179 with the pouch 178 by way of a duct 182 in the valve chest 168, so that the air entering the port 179 will raise the diaphragm 177, and lift the valve G' to close the suction port 173 and open the air admission port 172, see Fig. 14. The usual bleeder port 183 connecting the duct 182 with the suction chamber 174 equalizes the pressure on opposite sides of the diaphragm when its air inlet port 179 is closed. When the valve 15 G' has been raised as explained, air will pass by way of air port 172, duct 176, conduits 153^a and 153 to the pouches 148, and the pressure thereof will press the diaphragm against and seal the ports 141^a and 156^a as shown in 20 Fig. 14, and prevent the passage of air from the tracker B' to the primary pneumatics 18. Therefore, the speaking pneumatics 11 cannot be operated by the uncovering of the tracker ducts during the rewinding of the 25 note sheet over this tracker.

The valve G' is reversed to close port 172 and open port 173 to permit suction to act on the cutoff diaphragms 148 in the following manner:

30 As soon as the note sheet over tracker B' has been rewound, its winding perforation 85 will cause the collapse of the playing pneumatic 55, as before explained. The accompanying movement of pneumatic 56 causes it to engage the flap valve 180 and move it to close the air port 179, thus shutting off the air to the pouch 178 so that the diaphragm 177 will collapse and cause the valve G' to lower and close the admission 35 port 172, thereby permitting suction from the conduit 59 by way of the chamber 174 and port 173 to actuate the diaphragms 148, as previously explained. Therefore, when the note sheet moves in the playing direction over tracker B', the instrument will be 40 played.

The other cutoff valve G, see Figs. 2, 3 and 4 is constructed and operates in a similar manner, and is connected to the suction passage 68 of winding pneumatic 65 for the note sheet of mechanism A and to an air inlet port 185 by a conduit 186. The valve box 167 of the valve G connects with the set of pouches 147 by a conduit 187 connected to the suction conduit 151^a before described. It should be

understood that the valves G G' are opposed, so that one is open to the atmosphere, while the other is open to suction and the air control port of one valve is closed by one winding pneumatic, while the other is open. The 70 valve boxes are readily detachable from the brackets 58, 67 and are separable on the lines 188, 189 to permit easy access to their interiors for inspection or repairs.

It is desirable that the suction be broken 75 in the main suction bellows 14 when the friction pulley 48 is disconnected from the drive mechanism by the actuation of the crank shaft 50, so as to preclude possible operation of any of the suction actuated pneumatics or 80 devices of the instrument.

Means are provided for this purpose, preferably arranged as shown in Figs. 1 and 23. The crank shaft 50 is provided at its inner end with a fixed crank arm 190, which is connected by a link 191 to a lever 192 fulcrumed on a suitable fixed pivot 193 in the instrument case. As shown in Fig. 1, the main suction bellows 14 is provided with an air admission port 194, normally closed by a 85 spring pressed pallet 195 hinged at 196 to the bellows. The pallet 195 has a lateral arm 197, the free end of which extends above and adjacent the outer end 198 of the lever 192. When the crank shaft 50 is rotated 90 by the crank 52 to disconnect the friction pulley 48 from the cone pulley 49, as before explained, the arm 190 and link 191 will swing the lever 192 and, elevating its end 198, will move the arm 197 of the pallet 195. The pallet will therefore swing on its pivot 196 away from the air port 194 allowing air to enter the pneumatic 14 and break the suction therein.

I claim as my invention:

1. In a musical instrument the combination of a plurality of note sheets for separately controlling the operation of said instrument, an operating mechanism for each note sheet comprising a winding and rewinding roll for said note sheet, a shaft for each roll, a loose gear for each of said rolls, said gears being mounted for endwise movement on the respective roll shafts driven gearing meshing with both of said loose 110 gears, a clutch for imparting endwise movement thereto for each loose gear for coupling the same to its roll, and mechanism for simultaneously operating the several clutches to couple one of said loose gears for imparting endwise movement thereto for one note sheet to its roll and uncouple the other loose gear for said note sheet from its roll and 115 reversely operate the loose gears for another note sheet.

2. In a musical instrument the combination of a plurality of note sheets for separately controlling the operation of said instrument, an operating mechanism for each note sheet comprising a winding and re- 120

105

110

115

120

125

winding roll for said note sheet, a loose gear for each of said rolls, and each of which is axially alined with and is journalled for endwise movement relatively to its roll, connected drive shafts for the operating mechanisms for said note sheets, intermeshing gears connecting the drive shaft and both loose gears of each mechanism, a clutch for each of said loose gears for coupling the 5 same to and uncoupling it from its roll, and mechanism for simultaneously operating the several clutches of both of said mechanisms for reversing the travel of one sheet and starting the playing travel of another note 10 sheet.

3. In a musical instrument, the combination of a plurality of note sheets for controlling the operation of said instrument, a winding and rewinding mechanism for each 20 of said note sheets, each mechanism being a separate unit comprising a removable frame, winding and rewinding rolls, a shaft for each of said rolls rotatably mounted in said frame, a loose gear for each of said rolls 25 journalled on said roll shafts, a driving shaft journalled in said frame, gearing connected to said driving shaft and meshing with both of said loose gears on each of said respective roll shafts, a clutch for each of said 30 loose gears, for coupling it to and uncoupling it from each gear roll, said driving shafts of said mechanisms being coupled to each other to rotate together, and means for simultaneously operating the several clutches 35 of both of said mechanisms for causing the playing travel of one note sheet and the rewinding of the other note sheet.

4. In a musical instrument, the combination of a plurality of note sheets for controlling the operation of the instrument, winding and rewinding mechanisms for said 40 note sheets, including connected drive shafts for the several mechanisms, means for alternately connecting the winding and rewinding 45 rolls of each mechanism with its drive shaft, and a variable speed mechanism including a transmission shaft connected to and disposed in alinement with the drive shaft of one of said winding and rewinding 50 mechanisms and comprising a cone wheel, a friction wheel engaging said cone wheel, means for adjusting said friction wheel lengthwise relatively to said cone wheel for varying the speed of said drive shafts, and 55 means for moving said friction wheel into and out of engagement with said cone wheel for stopping and starting the drive shafts of said winding and rewinding mechanisms.

5. In a musical instrument, the combination of a pneumatic playing action, a note 60 sheet controlling said playing action, driving mechanism for said note sheet, a suction bellows operatively connected with said pneumatic playing action, a starting and 65 stopping device for said note sheet driving

mechanism, and means actuated by the operation of said starting and stopping device to break the suction in said suction bellows.

6. In a musical instrument, the combination of a pneumatic playing action, a note 70 sheet controlling said playing action, driving mechanism for said note sheet, a suction bellows operatively connected with said pneumatic playing action, driving means for said note sheet driving mechanism including wheels which are relatively movable for starting and stopping the note sheet driving mechanism, a device for disengaging said wheels to stop the note sheet driving mechanisms, and means operated by said device 75 for breaking the suction in said suction bellows when the note sheet driving mechanism is stopped.

7. In a musical instrument, the combination of a plurality of note sheets for controlling the operation of said instrument, a tracker for each note sheet, winding and rewinding mechanism for each note sheet, a playing and a rewinding pneumatic controlling the winding and rewinding mechanism for each note sheet, each note sheet having at the finish end thereof a rewinding perforation adapted to cooperate with the tracker and the rewinding pneumatic of that note sheet to cause the rewinding of 95 said note sheet during the playing of the other note sheets, and a perforation at the starting end of each note sheet cooperating with the tracker and the playing pneumatic of that note sheet to stop the rewinding 100 travel of said note sheet, and latch mechanism associated with the playing and rewinding pneumatics of the different note sheets for starting the playing travel of the rewound note sheet upon the completion of 105 the playing travel of the other note sheet.

8. In a musical instrument, the combination of a plurality of note sheets for controlling the operation of said instrument, a tracker for each note sheet, winding and 110 rewinding mechanism for each note sheet, pneumatic mechanism controlling the winding and rewinding mechanism for each note sheet, each note sheet having at its opposite ends perforations adapted to cooperate with 115 its tracker and through ducts to said pneumatic controlling mechanism to respectively cause the rewinding of said note sheet and to stop the note sheet when it is rewound, and means cooperating with said pneumatic 120 controlling mechanism for starting the playing travel of one note sheet simultaneously with the commencement of the rewinding of another note sheet.

9. In a musical instrument, the combination of a plurality of note sheets for controlling the operation of said instrument, a winding and rewinding mechanism for each note sheet, pneumatic mechanism operatively disposed between said note sheets and 130

said winding and rewinding mechanisms and operating automatically to cause the rewinding of each note sheet when it completes its playing travel, a latch mechanism associated with said pneumatic mechanism for arresting each note sheet when it is rewound, and means controlled by each note sheet when it commences to rewind, for simultaneously releasing said latch mechanism to start the playing travel of another note sheet.

10. In a musical instrument, the combination of a plurality of note sheets for controlling the operation of said instrument, a winding and rewinding mechanism for each note sheet, including clutches for each winding and rewinding mechanism for coupling the same to and uncoupling it from a drive shaft, a pneumatic actuating mechanism for the clutches of each winding and rewinding mechanism, means controlled by said note sheets for operating said pneumatic actuating mechanisms to cause the rewinding of one note sheet when it finishes its playing travel and simultaneously starting the playing travel of the second note sheet, and means controlled by each note sheet for arresting the same when completely rewound.

15. In a musical instrument, the combination of a plurality of note sheets for controlling the operation of said instrument, a winding and rewinding mechanism for each note sheet, including clutches for each winding and rewinding mechanism for coupling the same to and uncoupling it from a drive shaft, a pneumatic actuating mechanism for the clutches of each winding and rewinding mechanism, means controlled by said note sheets for operating said pneumatic actuating mechanisms to cause the rewinding of one note sheet when it finishes its playing travel and simultaneously starting the playing travel of the second note sheet, and means controlled by each note sheet for arresting the same when completely rewound.

20. In a musical instrument, the combination of a plurality of note sheets for controlling the operation of said instrument, a winding and rewinding mechanism for each note sheet, including clutches for each winding and rewinding mechanism for coupling the same to and uncoupling it from a drive shaft, a pneumatic actuating mechanism for the clutches of each winding and rewinding mechanism, means controlled by said note sheets for operating said pneumatic actuating mechanisms to cause the rewinding of one note sheet when it finishes its playing travel and simultaneously starting the playing travel of the second note sheet, and means controlled by each note sheet for arresting the same when completely rewound.

25. In a musical instrument, the combination of a plurality of note sheets for controlling the operation of said instrument, a winding and rewinding mechanism for each note sheet, including clutches for each winding and rewinding mechanism for coupling the same to and uncoupling it from a drive shaft, a pneumatic actuating mechanism for the clutches of each winding and rewinding mechanism, means controlled by said note sheets for operating said pneumatic actuating mechanisms to cause the rewinding of one note sheet when it finishes its playing travel and simultaneously starting the playing travel of the second note sheet, and means controlled by each note sheet for arresting the same when completely rewound.

30. In a musical instrument, the combination of a note sheet which controls the operation of the instrument, a winding and re-

winding mechanism for said note sheet, playing and rewinding pneumatics controlling respectively the playing travel and re-winding of said note sheet, a valve for each of said playing and rewinding pneumatics for alternately subjecting said pneumatic to suction and atmospheric pressure, an actuating pneumatic for each valve, and a passage controlled by each of said valves and connecting with the actuating pneumatic of the other valve whereby when one of said valves is actuated the other valve will be reversely actuated.

35. In a musical instrument, the combination of a pneumatic playing action, a plurality of note sheets and trackers controlling said playing action, winding and rewinding mechanism for said note sheets, pneumatic cut off devices for cutting off each tracker from the playing action during the rewinding of the note sheet for said tracker, pneumatic means for actuating said pneumatic cut off devices, dust screens, and conduits 40 operatively connecting said trackers, dust screens, cut off devices, and playing action, said dust screens and cut off devices being contained in boxes having removable covers at the same side thereof which are removable 45 to afford access to said screens and cut off devices.

45. In a musical instrument, the combination of a pneumatic playing action, a plurality of note sheets and trackers controlling said playing action, winding and rewinding mechanism for said note sheets, pneumatic cut off devices for cutting off each tracker from the playing action during the rewinding of the note sheet for said tracker, pneumatic means for actuating said pneumatic cut off devices, dust screens, and conduits 50 operatively connecting said trackers, dust screens, cut off devices, and playing action, said dust screens and cut off devices being contained in boxes having removable covers at the same side thereof which are removable 55 to afford access to said screens and cut off devices.

55. In a musical instrument, the combination of a pneumatic playing action, a plurality of note sheets and trackers controlling said playing action, winding and rewinding mechanism for said note sheets, pneumatic cut off devices for cutting off each tracker from the playing action during the rewinding of the note sheet for said tracker, pneumatic means for actuating said pneumatic cut off devices, dust screens, and conduits 60 operatively connecting said trackers, dust screens, cut off devices, and playing action, said dust screens and cut off devices being contained in boxes having removable covers at the same side thereof which are removable 65 to afford access to said screens and cut off devices.

CHRISTIAN MAERTEN.
